United States Patent Office.

L. ROBINSON, L. CONINE, N. F. HYATT, AND D. W. HYATT, OF MATTEAWAN, NEW YORK.

Letters Patent No. 91,670, dated June 22, 1869.

IMPROVEMENT IN FELTING-MACHINES.

The Schedule referred to in these Letters Patent and making part of the same.

To all whom it may concern:

Be it known that we, L. ROBINSON, L. CONINE, N. F. HYATT, and D. W. HYATT, of Matteawan, in the county of Dutchess, and State of New York, have invented a new and improved Machine for Felting Hat-Bodies; and we do hereby declare that the following is a full, clear, and exact description thereof, which will enable others skilled in the art to make and use the same, reference being had to the accompanying drawings, forming part of this specification.

This invention relates to improvements in machines for felting hat-bodies, designed to provide a means for accomplishing the same in a better manner than as at present done.

The invention consists in an arrangement of machinery for felting the tips of hats more evenly than can be done by the machines now in use. Also, for felting the sides, on a block so formed as to be inserted within the crown of the hat, the latter being turned thereon, to cause the whole to undergo the felting-operation, all as hereinafter more fully specified.

Figure 1 represents a longitudinal sectional elevation of our improved machine, taken on the line xx of fig. 2;

Figure 2 represents a plan view; and

Figure 3 represents a section on the line yy .

Similar letters of reference indicate corresponding parts.

In order to felt the hat-bodies on the tops of the crowns, we provide a vertical block, A, having a flat top, and provided with the ordinary heating-devices.

We place the bodies thereon, as represented in red at B, fig. 1, and perform the ordinary felting-operation upon the tops thereof, after which we remove them therefrom, and place them on the block C, as shown at D, fig. 3, so formed that it enters the interior space of the hat-bodies in a manner to interpose only the

single web between the block and the jigger E, or other felting-device, a portion only of the sides of the bodies being exposed to the felting-operation.

To subject the whole to the action of the jigger on the block, we turn the bodies slowly around as the operation progresses.

Hitherto the hat-bodies have been folded down into flat shape for felting, thin plates of pasteboard, or other suitable material, being placed between the two layers to prevent them from uniting under the felting-operation.

When so arranged, they were fitted in packs, upon a former similar to that represented at C, fig. 2.

Under this method, a seam is formed in the sides of the crown, extending over the top, where the fabric is not well felted, and the top is not as well finished as by our method, by which the seam is wholly avoided in the sides, and the top much more thoroughly felted. The employment of the dividing-plates is also avoided.

Having thus described our invention,

We claim as new, and desire to secure by Letters Patent—

The arrangement, in a felting-machine, of the formers A C, of the shape shown and described, with the jiggers E, for the purpose of felting the tips and bodies of hats at separate successive operations, substantially as herein shown and described.

The above specification of our invention signed by us, this   day of   , 1869.
